WILLIAM L. BARRON, OF NEW YORK, N. Y., AND FRITZ E. OSOL, OF ELIZABETH, NEW JERSEY, ASSIGNORS TO THE SINGER MANUFACTURING COMPANY, A CORPORATION OF NEW JERSEY.

PRESSER-FOOT-LIFTING MECHANISM FOR SEWING-MACHINES.

1,269,775.

Specification of Letters Patent. Patented June 18, 1918.

Application filed May 17, 1915. Serial No. 28,513.

To all whom it may concern:

Be it known that we, WILLIAM L. BARRON and FRITZ E. OSOL, citizens of the United States, residing, respectively, at New York, 5 in the county of New York and State of New York, and Elizabeth, in the county of Union and State of New Jersey, have invented certain new and useful Improvements 10 in Presser-Foot-Lifting Mechanisms for Sewing-Machines, of which the following is a specification, reference being had therein to the accompanying drawings.

This invention relates to presser-foot lifting mechanism for sewing machines and 15 especially machines in which the work is manually advanced between successive stitches, as in the operations of darning and patching.

It is common to the art to provide means 20 adapted to automatically lift the presser-foot at intermittent periods, and the present improvements comprise special presser-foot lifting means adapted to obviate the sudden contact of certain parts and consequent 25 shock when the presser-bar is released at the completion of the lifting movement thereof.

In the preferred embodiment of the improvements, as herein illustrated, a split collar is fitted upon the presser-bar, one 30 portion of the collar carrying a roller-stud fitted within the cam-slot of a cam-plate fulcrumed upon the collar in such position that when it is turned the walls of its cam-slot act upon the roller-stud to clamp the 35 collar firmly upon the bar preparatory to a lifting movement. The needle-bar is employed to lift the presser-bar, and to such end it is provided with a collar having a link connection with a cam-plate. A spring 40 surrounds the presser-bar and exerts a downward pressure on the split collar, so that the upward movement of the needle-bar first rocks the cam-plate upon its fulcrum to clamp the split collar upon the presser-bar. 45 and secondly lifts the presser-bar against the action of its spring. A tappet arm fulcrumed on the frame has a link connection with the cam-plate and this is caused to follow the turning and bodily upward movements of the latter. This tappet arm serves 50 as a stop to limit the downward movement of the clamping elements and, when the parts reach their lower position, the cam-plate is turned to release the presser-bar.

It will thus be seen that the link connection 55 between the tappet arm and the cam-plate prevents any sudden contact and consequent shock between these parts. The downward movement of the collar ceases just as the presser-foot reaches the work, and the 60 turning movement of the disk thereafter releases the presser-bar, so that the momentum of the latter is largely absorbed before it is released, and the foot gives a slight blow only to the work and throat-plate. 65

In the drawings, Figure 1 is a front elevation of the improvements applied to a sewing machine and Fig. 2 is a plan view, partly in section, of the same. Fig. 3 is a perspective view of the needle-bar, the 70 presser-bar, and certain connections. Fig. 4 is a perspective view, partly in section, of the cam-disk and its connections, and Fig. 5 is a rear elevation of the cam-disk and its connections. 75

The improvements are shown applied to a sewing machine comprising the bed A, standard B and overhanging head C, the latter being formed with suitable bearing apertures for the needle-bar 1, and the 80 presser-bar 2 carrying the foot 2^x. Loosely fitted upon the presser-bar is a collar 3 split at 3^x and formed with a threaded aperture at 4, to receive a stud-screw 5 serving as a fulcrum for a cam-plate comprising the 85 members 6 and 6^x secured together by means of the screws 7. The section 6 of the cam-plate is formed with the cam-slot 8 adapted to receive the roller-stud 9 carried by a plate 10 secured by means of the screws 11 90 to that portion of the collar opposite the threaded aperture 4.

The needle-bar is employed to lift the presser-bar at the proper time. To this end a collar 12 is fixed upon the needle-bar and 95 a link 13 connects the collar with the cam-plate at 14. The presser-bar is pressed downwardly by the usual plate spring 15, and surrounding the presser-bar is a coiled spring 16 which presses upon the upper face 100 of the split collar 3. Thus when the needle-bar rises the spring 16 acts to hold the collar motionless while the cam-plate 6 is turned through the instrumentality of link 13 to clamp the collar upon the presser-bar. 105 When the collar is clamped firmly upon the presser-bar the cam-plate ceases its turning movement and is carried upwardly with the

collar and presser-bar to lift the presser-foot above the work.

Fulcrumed at 17 upon a bracket 18 secured to the head C by means of the screws 5 19 is a tappet arm 20 held in contact with the periphery of cam-plate member 6^x by means of a link 21. Throughout the turning movement and bodily upward movement of the cam-plate, link 21 serves to hold the 10 tappet arm 20 pressed firmly against the periphery of the cam-plate member 6^x. Thereby on the downward movement of the needle noise and shock due to reciprocating parts is diminished if not altogether avoided. 15 In operation as the needle descends from its raised position, Fig. 1, to the cloth-plate, the split collar, together with the cam-plate 6 move bodily downward and link 21 turns tappet 20 about pivot 17. There is a 20 very slight rotation of cam-plate 6 about its pivot at this time. Then, before the needle and presser-foot reach the material and because of the retarding action of tappet 20 on surface cam 6^x the cam-plate 6 is turned 25 sufficiently about its pivot 5 to release the grip of the split collar on the presser-bar and to permit the presser-foot to engage the material being operated upon at about the time the needle reaches the goods. It will 30 be noted that when release of the presser-bar occurs, the foot will be thrust downward only by leaf-spring 15, the pressure of which may obviously be made as light or heavy as desirable. After the presser-bar is released 35 from the collar the weight of the parts operating the latter is largely carried by the collar 12 fast to the needle-bar. In this condition the operating devices constitute a floating linkage slidingly connected to the vertical presser-bar. It is to be further noted that the shape of the upper face of the tappet 20 and the edge of the surface cam 6^x secured to the cam 6 with which the tappet engages, is such that when the presser-foot 40 is engaged with the material the split collar 3 moves downwardly very little in proportion to the downward movement of the needle, thereby avoiding the shock and wear inseparable from rapidly moving reciprocating parts.

Because of this action the tappet arm 20 may be described as a retarding device for it acts to slow down the bodily vertical movement of the presser-bar very slightly 45 as the needle-bar descends from its raised position but sufficiently to compel rotation of cam-plate 6 whereby the presser-bar is released. Thereafter the tappet arm 20 is raised slightly as the toggle link 21 passes 50 over the line of centers of the pivot 5 and the pivotal connection of link 21 with tappet arm 20 which elevation of the tappet arm materially retards the downward movement of split collar 3 and its operating links. 55 The shape and arrangement of applicants'

linkage for automatically lifting and releasing the presser-foot is such that the parts lie compact and flat, thus enabling them to be arranged beneath the face-plate without unsightly projections. Furthermore a flat linkage and cam, arranged as is applicants', insures positiveness of action, both in gripping and releasing the bars when used with a split collar which is adapted to be constricted about the presser-bar in the manner of action found in a band-brake, the leading characteristic of which has been utilized in applicants' device. 75

It will be understood that various changes may be made in the form and arrangement 80 of the various elements herein shown and described without departing from the spirit of the invention. For example the cam-plate sections 6 and 6^x may be made integral, and means other than the link 13 may be 85 employed to connect the cam-plate with the needle-bar.

Having thus set forth the nature of the invention, what we claim herein is:—

1. In a presser-foot lifting mechanism, the 90 combination with a presser-bar, and a needle-bar, of a split collar embracing the presser-bar, a link connected to the needle-bar, and a cam-plate pivoted to the collar at one side of the split and operable on the 95 collar directly on the other side of the split to circumferentially constrict and grip the split collar like a band about the presser-bar.

2. In presser-foot lifting mechanism, the 100 combination with a reciprocatory actuating member, a presser-bar, and a collar surrounding the bar, of a rocking and bodily-movable lever adapted to constrict said collar, a connection between said lever and the reciprocatory actuating member, and a retarding device for the collar whereby the downward movement of the presser-bar is retarded for an interval immediately preceding its release. 105

3. In a sewing machine, the combination 110 with a presser-bar and a needle-bar, of a split collar embracing the presser-bar, a cam-plate pivoted upon the collar and adapted to constrict the same about the presser-bar, a link connecting the cam-plate and the 115 needle-bar, a tappet arm fulcrumed upon the frame, and a link connection between the tappet arm and the cam-plate.

4. The combination with a presser-bar and a split collar embracing the same and carrying a stud, of a cam-plate pivoted upon the collar and adapted to act upon the stud to constrict the collar, and means for turning said plate upon its pivot to constrict the collar and subsequently impairing a bodily 125 upward movement thereto.

5. In a sewing machine, the combination 130 with a presser-bar and a reciprocatory member, of a split collar embracing the presser-bar and carrying a stud, a cam-plate pivoted

upon the collar and adapted to act upon the stud to constrict the collar, a link connecting the cam-plate and the reciprocatory member, a tappet-arm fulcrumed upon the frame, and a link connection between the tappet-arm and the cam-plate.

5 6. In a presser-foot lifting mechanism, the combination with a reciprocatory actuating member, a presser-bar, and a split collar surrounding the bar, of a rocking and bodily movable cam-plate adapted to constrict said collar upon the presser-bar, and carrying a surface cam, a connection between said cam-plate and the reciprocatory actuating member, and a retarding device for the collar and its actuating parts whereby the downward movement thereof relative to the needle is materially diminished, said retarding device including an arm in sliding and rolling engagement with said surface cam secured to the rocking and bodily movable cam-plate.

10 7. In a presser-foot lifting mechanism, the combination with a reciprocatory actuating member, a presser-bar, a split collar surrounding the bar, of a rocking and bodily movable cam member adapted to intermittently constrict said collar about said presser-bar, a connection between said cam-member and said reciprocatory actuating member, and a retarding device for the collar, whereby the downward movement of the collar and its actuating mechanism is retarded, said device including a toggle link.

15 8. In a presser-foot lifting mechanism, the combination with a reciprocatory actuating member, a presser-bar, a split collar surrounding the bar, of a rocking and bodily movable cam member adapted to intermittently constrict said collar about said presser-bar, a connection between said cam member and said reciprocatory actuating member, a retarding device for the collar, whereby the downward movement of the collar and its actuating mechanism is retarded, said retarding device including a toggle link and a tappet-arm pivoted to the frame of the machine and connected to said toggle link, said toggle link being also connected to said rocking and bodily movable

20 cam member.

9. In a presser-foot lifting mechanism for sewing machines having stitch-forming

mechanism including a needle and a head carrying the same, in combination, a presser-bar, a band-like member encircling the 55 presser-bar, said member being split at one point in its circumference, and means at the opposite ends of said band adjacent said split for circumferentially approaching said ends to cause the member to grip the bar, 60 said means including a linkage entirely inclosed within the outline of the head.

10 10. In a presser-foot lifting mechanism for sewing machines having stitch-forming mechanism including a needle, in combination, a presser-bar, a band-like member 65 encircling the presser-bar, said member being split at one point in its circumference, means at the opposite ends of said band adjacent said split for circumferentially approaching said ends to cause the member to grip the bar, means for lifting said presser-foot simultaneously with the needles including a toggle-actuated retarding device for lowering the presser-foot at a slower speed than 70 the needle.

15 11. In a presser-foot lifting mechanism for sewing machines having stitch-forming mechanism including a needle, in combination, a presser-bar, a band-like member 75 encircling the presser-bar, said member being split at one point in its circumference, means at the opposite ends of said band adjacent said split for circumferentially approaching said ends to cause the member to grip the bar, and positive means for lowering the presser-foot to a position substantially on the work and releasing it.

20 12. In a sewing machine for darning and having stitch-forming mechanism including 80 a needle in combination, a spring-pressed presser-bar, a presser-foot carried thereby, means for intermittently clamping said bar, said means acting positively to lower the presser-foot to a position substantially in 85 contact with the material and then releasing the presser-bar to permit the foot to impinge against the material under the action of its own spring.

25 In testimony whereof, we have signed our 100 names to this specification.

WILLIAM L. BARRON.

FRITZ E. OSOL.
